UNITED STATES PATENT OFFICE.

EDMUND O. SCHWEITZER, OF CHICAGO, ILLINOIS, ASSIGNOR TO ASSOCIATED
ENGINEERS COMPANY, OF CHICAGO, ILLINOIS.

ILLUMINATING DEVICE.

1,098,592.

Specification of Letters Patent. Patented June 2, 1914.

Application filed March 4, 1912. Serial No. 681,461.

To all whom it may concern:

Be it known that I, EDMUND O. SCHWEITZER, a citizen of the United States, residing at Chicago, in the county of Cook and State 5 of Illinois, have invented a certain new and useful Improvement in Illuminating Devices, of which the following is a full, clear, concise, and exact description, reference being had to the accompanying drawings, 10 forming a part of this specification.

My invention relates to illuminating devices and systems and has for its object the provision of means whereby the failure of one illuminating device of a system will not 15 cause the inoperativeness or failure of other devices of the same system.

One system in which my invention finds great use is in connection with illuminating systems in which a plurality of devices, for 20 instance incandescent lamps, are connected in series. To be more specific so far as this particular application of the invention is concerned, it may be said that in electrical signs, for instance, which are served from 25 an electrical source of one hundred and fifteen volts potential, that ten lamps of twelve volts each are preferably connected in series to form a bridge across this source of current. Usually more than one bridge is 30 needed to complete the sign although of course the number of bridges has nothing whatever to do with the invention. These lamps are of small candle power and are usually of thirty ohms resistance. It will 35 be apparent that should one of these lamps become extinguished by reason of the filament breaking or some other defect, that quite a void would be left in the sign by the extinguishment of this particular lamp and 40 the other nine lamps in series therewith. Thus if there were four bridges in the system the failure of one lamp might nullify the effect of twenty-five per cent. of the sign, or the failure of merely three lamps 45 out of forty might nullify the effect of seventy-five per cent. of the sign. It is essential therefore that some means be provided to overcome this very objectionable feature of the series connection, although 50 such arrangement of the lamps is by far the most economical in order to secure low candle power lamps, and economical wiring plans. My present invention concerns itself with eliminating this defect in the particular instance under consideration, or other

equivalent instances as will be readily apparent.

Generally speaking the form of my invention which I have illustrated herein and which is one embodiment of my invention 60 comprises suitable means voltage controlled which form a bridge or other satisfactory electrical connection about the lamp which has failed so that the rest of the lamps may continue burning. The devices operate automatically. I will describe this embodiment of my invention in connection with the accompanying drawing, in which—

Figure 1 is a side view of my improved lamp; Fig. 2 is a sectional view more clearly 70 to reveal the connections; Fig. 3 shows a modification in which two filaments may be used, and Fig. 4 shows the circuit arrangement, one of the devices having operated.

Referring more particularly to Fig. 1, I 75 show a lamp 1 having a filament 2, which filament is associated respectively with the annular screw threaded contact element 3 and the centrally located connecting stud 4 as is customary. The lamp, of course, as 80 is customary fits into some suitable receptacle as is well understood so that its elements 3 and 4 are connected to points of unlike potential to thereby illuminate the lamp. Now in my improved lamp I provide 85 additional means which may be placed in shunt of the filament 2 whenever this filament breaks. These means are more clearly illustrated in Fig. 2 in which the stud 4 projects into and is fastened to the 90 normal rear contact 5 of the lamp. The filament 2 as is apparent, of course, connects with the shell 3 and contact 5. On top of this contact 5, I mount a disk 6 of material of reasonably high resistance pref- 95 erably equal to the resistance of the filament 2. This element 6 may be carbon or other similar material giving the required resistance. The upper surface of this disk 6 is provided with a coating of shellac or lacquer 100 or other insulating material 7. Surmounting this shellac is a disk of copper 8. The elements 6, 7 and 8 are prevented from engaging the stud 4 by means of the tube 9 of insulation as shown. Surmounting the copper disk 8 is a sheet of mica 10 and a nut 11 holds all the elements in place upon the stud 4. The copper plate 8 by means of a strip 12 is in metallic connection with the screw threaded she 3 of the lamp. It will be 110

seen from this that the stud 4 and the nut 11 are insulated from the shell 3 and copper plate 8 by means of the mica 10 and the sleeve 9. The high resistance element 6 is, 5 however, in permanent electrical contact with the stud 4 through the rear conducting plate 5. The shellac 7 separates the copper plate 8 electrically from the disk 6. Normally therefore the circuit of the stud 4 10 is through the filament 2 and back to the shell 3. Now should this filament 2 break, then immediately across this bridge or between the elements 8 and 6 a difference of potential equal to the total circuit voltage, 15 namely, one hundred and fifteen volts exists as will be readily apparent by inspecting Fig. 4. Now immediately this extreme potential is established across the elements 8 and 6, this potential breaks down the insulation 7 and permits fusion or other satisfactory electrical contact between the elements 8 and 6. The circuit from the stud 4 20 to the shell 3 may then be traced from the shell 3, strip 12, plate 8, disk 6, conducting plate 5 to the stud 4. In other words there has been substituted in the circuit to replace the broken filament 2 a high resistance element 6 equal or substantially equal in resistance to the resistance of the filament 2. 25

30 In Fig. 3 I have set forth a lamp in which the high resistance element 6 is replaced by a second filament 13, which filament takes the place of the ruptured filament so as to continue the illumination of the lamp.

35 It is of course readily apparent that the parts 6, 7, 8, 9, 10 and 11 may be countersunk within the lamp shell 3, if so desired, to provide a more inclosed article. Likewise these elements may be placed in the 40 socket if desired instead of upon the lamp as will readily suggest itself to those skilled in the art.

In Fig. 4 I have shown the circuit in which a plurality of lamps, indicated by the 45 filaments 2, are shown in series relation with a source of current 14. The spark

gaps are illustrated in diagram by the elements 6 and 8 and these elements 6 and 8 are shown as fused together in the right hand lamp by the rupture of the right hand filament 2, thus maintaining the continuity of the circuit without substantial change in the resistance of said circuit. 50

It will of course be apparent that many modifications within the scope of the appended claims may be made in the specific description above set forth without departing from the spirit of my invention. 55

Having, however, thus described one embodiment of my invention, what I claim as new and desire to secure by Letters Patent is:

1. An incandescent lamp having a base portion, a centrally located contact terminal thereon, an annular contact element thereon, 65 a pair of terminals on said base separated by a spark gap adapted upon undue rise in potential to connect centrally located contact with said annular contact, and a stem protruding from said base portion 70 upon which said spark gap terminals are mounted.

2. An incandescent lamp having a base portion, a centrally located contact terminal thereon, an annular contact element 75 thereon, a pair of terminals on said base separated by a spark gap adapted upon undue rise in potential to connect said centrally located contact with said annular contact, and a stem protruding from said base 80 portion upon which said spark gap terminals are mounted, one of said spark gap terminals being normally insulated from said stem.

In witness whereof I hereunto subscribe 85 my name this 17th day of February, A. D., 1912.

EDMUND O. SCHWEITZER.
